UNITED STATES PATENT OFFICE.

HENRY H. LAMPERT, OF CHICAGO, ILLINOIS.

SUPPORT AND SPACER FOR REINFORCING BARS.

Application filed December 18, 1923. Serial No. 681,379.

To all whom it may concern:

Be it known that I, HENRY H. LAMPERT, a citizen of the United States of America, and a resident of Chicago, county of Cook, and State of Illinois, have invented a new and useful Improvement in Supports and Spacers for Reinforcing Bars, of which the following is a specification.

This invention relates to the reinforcing means for concrete structures, particularly beams, and the object of the invention is to provide a suitable support and spacer for the reinforcing bars whereby these may be fixed in position at any desired specified distance apart without inconvenience or making a change in the supporting and spacing means. It is incidentally the purpose of the invention to provide a construction which may be made in stock lengths and cut to suit any width of beam.

The objects of the invention may be accomplished by the construction shown in the drawings, wherein—

Figure 1 is a plan view of a reinforcing bar spacer and support, showing one bar in place thereon.

Fig. 2 is a front elevation, partly in section, of the construction shown in Fig. 1.

Fig. 3 is a sectional detail taken along the line 3—3 of Fig. 1.

Fig. 4 is a front elevation of a somewhat modified construction adapted to support a plurality of rows of vertically spaced horizontal bars.

Fig. 5 is an end elevation, partly in section, of the construction shown in Fig. 4.

Fig. 6 is a perspective view illustrating different forms of chairs or supports for the reinforcing bars.

The construction to which the invention relates consists mainly of a uniformly perforated strip of metal, preferably channel-shaped, the perforations being spaced apart about a distance equal to the diameter of a standard reinforcing bar so that these bars may be laid crosswise of the channel strips at different desired points and still be in position to be secured to the channel bars by wires passing over the reinforcing bars, and through the perforations in the channel bars.

In addition, the perforations in the channel bars receive tab-shaped projections of sheet metal supports. These supports may be of various forms, as illustrated in the drawings, but preferably as shown in Figs. 1 to 3. The sheet metal supports are

suitably bent to properly support the channel bars, and the projecting tabs thereon are bent over into locking engagement with the bars.

Referring to the drawings, the U-shaped channel bars 1 are shown as having the uniformly spaced circular perforations 3. The perforations 3 receive the tabs 4, projecting upwardly from sheet metal supports 5 for the channel bar. The tabs 4 are bent over against the web of the channel bar to secure the supports 5 to the bar. The reinforcing bars 6 are laid over the channel bars crosswise thereof and secured to the same in any desired position by wires passing over the reinforcing bar and through the perforations 2. As shown in Fig. 3, the supports 5 are punched from sheet metal strips without loss of material, as the tabs 4 for one support are cut from the stock of 65 another support, leaving the cut-out spaces 70 75 9 therein.

The supports 5 before being applied to the channel bars are bent into what is known as Z form, as shown in Fig. 1, so as to substantially resist being accidentally bent toward the channel bar, a common occurrence with some other types of supports and which it is desired to avoid in order to assure 80 that the reinforcements will be placed the proper distance from the bottom of the form. The perforations 3 are staggered, as shown in the drawing, in order to receive 85 the tabs 4 of sheet metal supports of this Z 90 form. This arrangement of perforations is also convenient for wiring the reinforcing bars 6 to the channel bars in any desired location.

Figs. 4 and 5 illustrate substantially the 95 same construction, except that the sheet metal supports 5 in this case are cut away as at 10 to provide a rest for one of the channel bars 1. With this modification, a plurality of vertically spaced rows of reinforcing bars 6 may be properly supported, the sheet metal supports 5 in this case at 100 times being turned upside down.

Fig. 6 shows various modifications of the sheet metal supports 5 for use in certain 105 classes of work. These modifications are respectively indicated as 11, 12 and 13.

In the use of the construction illustrated, the channel bars 1 and sheet metal supports 5 are secured together before shipment to 110 the place where used. Then, all that the concrete worker need do to lay the reinforce-

ment is to set these on the forms at the required distances apart, and then place upon the supports the necessary number of reenforcing bars.

5 I claim:

A support for reenforcing bars comprising a channel bar, the web of which is provided with rows of perforations, the perforations being uniformly spaced in each row,

10 but the perforations of one row being stag-

gered with respect to the perforations of the adjacent row, sheet metal supports for said channel bar, said sheet metal supports being bent into Z form and provided with projections extending through said apertures 15 and bent down against the web of the channel bar.

Signed at Chicago this 14 day of Dec. 1923.

HENRY H. LAMPERT.

ment is to set these on the forms at the required distances apart, and then place upon the supports the necessary number of reenforcing bars.

5 I claim:

A support for reenforcing bars comprising a channel bar, the web of which is provided with rows of perforations, the perforations being uniformly spaced in each row,
10 but the perforations of one row being stag-

gered with respect to the perforations of the adjacent row, sheet metal supports for said channel bar, said sheet metal supports being bent into Z form and provided with projections extending through said apertures and bent down against the web of the channel bar.

Signed at Chicago this 14 day of Dec. 1923.

HENRY H. LAMPERT.

Certificate of Correction.

It is hereby certified that in Letters Patent No. 1,556,151, granted October 6, 1925, upon the application of Henry H. Lampert, of Chicago, Illinois, for an improvement in "Supports and Spacers for Reenforcing Bars," an error appears requiring correction as follows: In the heading of the drawings the name of the patentee is erroneously printed as "H. H. Lambert," whereas said name should have been printed as "H. H. Lampert"; and that the said Letters Patent should be read with this correction therein that the same may conform to the record of the case in the Patent Office.

Signed and sealed this 10th day of November, A. D. 1925.
